VISIBLE MULTIPLE SIGNAL INDEX CARD
AND SYSTEM

Horace B. Holland, Woodside, N. Y.

Application December 20, 1933, Serial No. 703,160

23 Claims. (Cl. 129—16)

This invention relates to index card signal systems, the object of the invention being to provide an improved visible multiple signal index card system adapted for various purposes 5 but particularly adapted for use as a stock record simple in construction, inexpensive to manufacture and readily assembled in a suitable binder such as a loose-leaf binder.

A further object of the invention is the provision of a series of sheets or cards, each sheet comprising a single card folded upon itself to provide a pair of sections, one having along its length an exposed margin for the reception, for instance, of a scale of stock prices, such scale 10 being segmentally located and between which sections one or more pivoted indicating devices are shiftable to register with such scale.

A further object of the invention is the provision of an improved duplex sheet or card so 15 folded upon itself as to provide along the lengthwise margin thereof, an exposed portion for the reception of data, which card may be readily and quickly stamped from a single sheet of paper or cardboard.

In the drawings accompanying and forming a part of this specification, Fig. 1 illustrates this 20 improved visible multiple signal index card system arranged in a loose-leaf binder with the several sheets or cards resting flat-wise, one upon another, whereby the margins of the several 25 cards are exposed for a quick reading thereof.

Fig. 2 is a perspective view of one of the cards detached from its binder.

Fig. 3 is a detail cross sectional view illustrating one form of means that may be used for mounting the signal devices or arrows between the pair of sections of each sheet.

Fig. 4 is a view of a blank from which the 30 cards are folded.

Fig. 5 illustrates another form of card with a modification of the signal devices that may be used.

Fig. 6 is a view illustrating two cards with the 35 modified form of indicators in position, and

Fig. 7 is a detail of the modified form of indicator.

Similar characters of reference indicate corresponding parts in the several views.

Before explaining in detail the present improvement and mode of operation thereof, I desire to have it understood that the invention is not limited to the details of construction and arrangement of parts illustrated in the accompanying drawings since the invention is capable 50 of other embodiments, and that the phrasology which I employ is for the purpose of description and not of limitation.

Any number of cards may be assembled in the 55 binder, for instance, a loose-leaf binder, and various means may be used for such assemblage.

In the present instance, each card is provided with a pair of metal clips 20 clamped thereto and adapted to receive a binding wire 21 carried by the binder 22, and these binding wires are so located relative to the back that when the sheets 5 are laid flat, one upon another, all data carrying margins are exposed.

Each card is made from a blank 2 of paper, celluloid, cardboard or any other desired material of suitable size and shaped in the manner shown in Fig. 4 in which the free perpendicular edges 3 and 4 are segmentally formed to provide curved or convex edges terminating in straight marginal edges 5 and 6, the straight edges of the left-hand portion or section 7 being suitably notched as at 7' so that when the card is folded lengthwise centrally thereof, the curved edge of the right hand portion or section 8 will form a projecting margin 9 extending beyond the curved edge of the left hand portion or section 7, 15 although it will be understood that the same result could be obtained by dispensing with the notch and folding the sheet other than centrally thereof lengthwise whereby the right-hand section would be wider than the left one. 25

The exposed marginal portion 9 may be used for the reception of any suitable data and, in the present instance, it is shown as containing a scale of stock prices.

The straight tabs 10 at the ends of the curved portion may be used for the reception of the name of the stock or other desired commodity, and various memoranda or data may be applied to the outer face 11 of the section 7 or to the rear face of the section 8 or either may be used to write 30 upon.

Located between the folded section of each sheet are a plurality of indicators or signal devices 12 shown in several of the figures as of arrow formation. They are pivotally supported 40 between the sections of each sheet by a suitable rivet 13 or otherwise, suitable spacing washers 14 being used between the ends of the arrows to provide for the proper manipulation of one without moving the others. These indicators, as 45 stated, may be in the form of arrows or hands having indicating points or arrow heads or may be in the form shown in Fig. 5, in which they are provided with ends 15 overlapping the curved margin of the data carrying section whereby they 50 may be shifted along the same to any desired point. In this Fig. 5, the straight portion 5 does not cover the straight portion 6.

Thus, when the sheets are used for the purpose of indicating the varying prices of stock, one section, for instance, may be marked on the upper end tab thereof to indicate U. S. Steel 55 stock and have along the exposed margin thereof the scale of prices of that stock while a section 60

of another sheet may be marked American Can and so on.

At the close of the day, one indicating hand may be positioned to indicate the low prices of the stocks for that day, another indicating hand positioned to illustrate the high prices of the stocks for that day and another hand positioned to indicate any other desired information in connection therewith so that the assembled sheets 10 will indicate at a glance the varying prices during the day or any period that may be desired of a series of stocks, and when the sheets are assembled in the manner shown in Fig. 1, the user may at a glance know the varying prices of a large 15 series of stocks by merely looking along the exposed edges of the sheet, it being understood, of course, that these sheets will be placed in a binder in some manner similar to that shown in Fig. 1, wherein, when they are resting flat in said binder, 20 the exposed margin of a succeeding card or sheet will extend beyond that of the preceding card or sheet, enabling the user at a glance to know the high or low or any other fact connected with a large number of stocks without the necessity of 25 poring through various memoranda or other matter to ascertain these facts. Thus, the user, for instance, sitting before a stock board in a broker's office with his memorandum book in hand could quickly tell the high and low of a great number 30 of stocks as they existed the day before or for any predetermined period of time according to the way he has set his signalling hands without the necessity of making inquiry or reading various records to ascertain this information and 35 thus can carry in his pocket all the necessary records of a series of stocks.

This invention therefore provides a very simple, inexpensive and comprehensive record readily manipulated to suit the convenience and desire 40 of the user, at the same time providing a simple and efficient memorandum book for the recording of information therein relative to the individual stock or other commodity for, obviously, the improvement is not limited to the recording 45 of stocks but may be used in connection with any other commodity or variable as, for instance, to indicate in the same manner the high and low prices of a commodity that may have been purchased by a store at any time and any variations 50 thereof.

Of course, the indicating hands may be of different colors and may be made of some inexpensive material such as celluloid or heavy paper provided with pointed ends, or such pointed 55 ends may be clipped thereto so that, for instance, when colored hands are used, the red hand may indicate the low price, the white hand the high price and the blue or any other colored hand some intermediate price.

60 It will be observed that the curved edges of the sheets are struck from the pivotal center of the indicating hands. Of course, it would be practical in some forms to have the same circularly moving hands, provided the data was located in 65 segmental form on straight cut sheets, but the present form of the invention requires less stock and is, therefore, more economical.

In practice, it is preferable to have the sections of each card connected at their ends, thus 70 forming an envelope or pocket in which the indicating devices or arrows are located. This facilitates the handling of each card since the section of each card will not open independently of its companion section. This arrangement also facilitates binding of the cards at one end instead of 75

along their folded edge when this is desirable. Various ways of connecting these cards at the ends may be used, the simplest being the use of well known paper clips as illustrated at 25, Fig. 6.

It is to be understood that, by describing in 5 detail herein any particular form, structure or arrangement, it is not intended to limit the invention beyond the terms of the several claims or the requirements of the prior art.

Having thus explained the nature of my said 10 invention and described a way of constructing and using the same, although without attempting to set forth all of the forms in which it may be made or all of the modes of its use, I claim:

1. A visible multiple signal index card system 15 comprising a series of duplex sheets, one section of each sheet having a data receiving margin projecting beyond the edge of its companion section, the several sheets assembled to have all of the projecting margins simultaneously exposed 20 when the sheets rest flatwise, one upon the other, and pivoted indicating devices located between the pair of sections of each sheet and shiftable to indicate the different data thereon.

2. A visible multiple signal index card system 25 comprising a series of duplex sheets, one section of each sheet having a curved data receiving margin projecting beyond the edge of its companion section, the several sheets assembled to have all of the projecting margins simultaneously exposed 30 when the sheets rest flatwise, one upon the other, and pivoted indicating devices located between the pair of sections of each sheet and shiftable to indicate the different data thereon.

3. A visible multiple signal index card system 35 comprising a series of duplex sheets, one section of each sheet having a data receiving margin projecting beyond the edge of its companion section, the several sheets assembled to have all of the projecting margins simultaneously exposed 40 when the sheets rest flatwise, one upon the other, and pivoted indicating devices located between the pair of sections of each sheet and shiftable to indicate the different data thereon, the free edge of each section having a curved 45 form struck from the pivotal center of the indicating devices.

4. A visible multiple signal index card comprising a sheet folded upon itself to have one marginal edge projecting beyond the other for 50 the reception of data located thereon in segmental or arc form and an indicating device between the folds of the sheet and shiftable in an arcuate path to indicate the different data 55 thereon.

5. A visible multiple signal index card blank 60 cut from a single sheet with its opposite marginal edges of curved form and folded to form a pair of sheets, and an indicating device between the folds of the sheet and shiftable in an arcuate path to indicate the different data thereon.

6. A visible multiple signal index card comprising a sheet folded upon itself to have one marginal edge projecting beyond the other for the reception of data, each such edge having a segmental or arc form and terminating in a straight tab for the reception of indicia. 65

7. A visible multiple signal index card comprising a sheet folded upon itself to have one marginal edge projecting beyond the other for the reception of data, each such edge having a segmental or arc form and terminating in straight tabs at opposite ends. 70

8. A visible multiple signal index card comprising a sheet folded upon itself to have one mar- 75

ginal edge projecting beyond the other for the reception of data, and a plurality of indicating means located between the folds of the sheet and shiftable to indicate the different data thereon.

5 9. A visible multiple signal index card comprising a sheet folded upon itself to have one marginal edge projecting beyond the other for the reception of data located thereon in segmental or arc form, and a plurality of pivotally supported 10 indicating means located between the folds of the sheet and shiftable to indicate the different data thereon.

10 10. A visible multiple signal index card comprising a sheet folded upon itself to have one marginal edge projecting beyond the other for the reception of data, each such edge having a segmental or arc form, and a plurality of pivotally supported 15 indicating means located between the folds of the sheet and shiftable to indicate the different data thereon.

20 11. A visible multiple signal index card comprising a sheet folded upon itself to have one marginal edge projecting beyond the other for the reception of data, each such edge having a segmental or arc form and terminating in a straight tab for the reception of indicia, and a plurality of pivotally supported 25 indicating means located between the folds of the sheets and shiftable to indicate the different data thereon.

30 12. A visible multiple signal index card comprising a sheet folded upon itself to have the marginal edge of one section projecting beyond the other for the reception of data, and an indicating hand pivotally supported between the 35 sections adjacent to the folded portion thereof, the data being located on the projecting marginal edge in segmental formation struck from the pivotal center of the hand.

40 13. A visible multiple signal index card comprising a sheet folded upon itself to have the marginal edge of one section projecting beyond the other for the reception of data, and an indicating hand pivotally supported between the 45 sections adjacent to the folded portion thereof, the marginal edges of the sheet each having a curved formation struck from the pivotal center of the indicating hand.

50 14. A visible multiple signal index card comprising a sheet folded upon itself to have the marginal edge of one section projecting beyond the other for the reception of data, and an indicating hand pivotally supported between the 55 sections adjacent to the folded portion thereof, the marginal edges of the sheet each having a curved formation struck from the pivotal center of the indicating hand and terminating in a straight formed tab for the reception of indicia.

60 15. A duplex card comprising a pair of superposed sections having curved free edges, one section being of less width than the other throughout the major portion thereof, thereby forming an exposed margin for the reception of data and an indicating device between the sections and shiftable in an arcuate path to indicate the different data thereon.

65 16. A duplex card comprising a pair of sections formed from a single folded sheet and having curved free edges, one section being of less width than the other throughout the major portion thereof, thereby forming an exposed margin for the reception of data and an indicating device between the sections and shiftable in an arcuate path to indicate the different data thereon.

70 17. A duplex card comprising a pair of sections formed from a single folded sheet and having

curved free edges, one section being of less width than the other throughout the major portion thereof, thereby forming an exposed margin for the reception of data, and shiftable indicating devices pivotally located intermediate of the sections and adjacent to the folded edge thereof and projecting beyond the margin of the section of less width, the section of greater width having the data thereof in segmental form struck from the pivoted center of the indicating devices. 10

15 18. A duplex card comprising a pair of sections formed from a single folded sheet and having curved free edges, one section of less width than the other throughout the major portion thereof, thereby forming an exposed margin for the reception of data, and shiftable indicating devices pivotally located intermediate of the sections and adjacent to the folded edge thereof and projecting beyond the margin of the section of less width, the section of greater width having the 20 data thereof in segmental form struck from the pivoted center of the indicating devices, and spacing means between the pivoted ends of the indicating devices.

25 19. A record system comprising a plurality of duplex record cards, each card folded upon itself to form a pair of sections, both having segmental edges and one being of less width than the other thereby forming an exposed data receiving margin, one segmental edge terminating in a straight indicia receiving margin, and a plurality of pivoted indicating markers shiftable relative to said data receiving margin and located between the sections of each card to project beyond the section of less width. 30

35 20. A record system comprising a plurality of duplex record cards, each card folded upon itself to form a pair of sections, both having segmental edges and one being of less width than the other thereby forming an exposed data receiving 40 margin, one segmental edge terminating in a straight indicia receiving margin, and a plurality of pivoted indicating markers shiftable relative to said data receiving margin and located between the sections of each card to project beyond 45 the section of less width and each marker having its outer end overlapping the curved edge of the section of greater width.

50 21. A visible multiple signal index card comprising a sheet folded upon itself to have one marginal edge projecting beyond the other for the reception of data, a plurality of indicating means located between the folds of the sheet and shiftable to indicate the different data thereon, and means for securing the ends of the folded 55 sheet together.

60 22. A visible multiple signal index card comprising a sheet folded upon itself to have one marginal edge projecting beyond the other for the reception of data, indicating means located between the sheets and shiftable to indicate the different data thereon, and means for securing the ends of the folded sheet together. 60

65 23. A visible multiple signal index card system comprising a series of duplex sheets, one section of each sheet having a data receiving margin projecting beyond the edge of its companion section, the several sheets assembled to have all of the projecting margins simultaneously exposed when the sheets rest flatwise, one upon the other, pivoted indicating devices located between the pair of sections of each sheet and shiftable to indicate the different data thereon, and means for securing the ends of each folded sheet together. 70
